UNITED STATES PATENT OFFICE.

JOHN E. MUHLEFELD, OF SCARSDALE, NEW YORK.

LOCOMOTIVE ENGINE.

Application filed June 26, 1925. Serial No. 39,675.

This invention relates to locomotive engines, and more particularly to an engine of the three cylinder type, the primary object of my present improvements residing in the 5 mounting and arrangement of the middle or third cylinder with respect to the side cylinders and the connection of said third cylinder with the front side frames and with the main frame members whereby an exceedingly durable and substantial construction and one 10 which may be manufactured at comparatively small cost is attained.

The prominent and distinguishing feature 15 of my present invention resides in the unique and unusual integral construction of the middle or central cylinder, the side frames and the boiler cylinder saddle.

In one practical embodiment of the invention, I provide in the form of a single integral casting, the two front side frames and the middle or central cylinder with its valve chest and the boiler cylinder saddle extending above the engine cylinder. Provision is made on said side frames for the connection 25 of the side cylinders therewith preferably in line with the central or middle cylinder transversely of the structure whereby said central cylinder and its integral connection with the side frames rigidly reinforces and strengthens 30 the side frames against the mechanical stresses induced by the weight of the side cylinders and their valve chests.

With the above and other objects in view, the invention consists in the improved locomotive engine structure and in the form, construction and relative arrangement of the several parts as will be hereinafter more fully described, illustrated in the accompanying drawings, and subsequently incorporated in 40 the subjoined claims.

In the drawing, wherein I have illustrated one simple and satisfactory embodiment of the invention, and in which similar reference characters designate corresponding parts throughout the several views,—

Figure 1 is a vertical transverse section taken substantially on the line 1—1 of Fig. 2, and

Fig. 2 is a vertical longitudinal section 50 taken on the line 2—2 of Fig. 1.

Referring in detail to the illustrated embodiment of the invention, the two parallel side frames 5 which have heretofore been separately formed or cast, are in the present 55 instance cast as a single integral structure, said side frames intermediate of their ends

each having a vertically extending substantially rectangular portion 6. These intermediate portions of the side frame members are integrally connected with the central or 60 middle engine cylinder 7 by means of the transverse wall or web 8 and below said cylinder and also between the side frames 5 the cylinder valve chest 9 is integrally formed with the wall 8. However, while I have herein shown the valve chest as being arranged below the engine cylinder, it will be understood that this valve chest may, if desired, be positioned above the said cylinder. The integral connecting wall 8 is extended above the 70 cylinder 7 and is formed with a one-piece saddle 10 in which the front end of the boiler cylinder 11 is seated and securely bolted thereto in the usual manner.

Each of the side frames 5 is also formed 75 with a forwardly projecting bumper carrying extension 12 and with a part 13 projecting rearwardly of the middle cylinder 7. These rearward extensions 13 of the side frames are integrally connected at their upper edges by the horizontally positioned transversely disposed wall or web 14. To each of these rear extensions 13 of the side frames one of the longitudinal main frame members 15 of the locomotive structure is 80 bolted or otherwise rigidly fixed at its forward end.

It is possible to also cast the side cylinders and their valve chests integral with the side frame members 5, but I preferably employ 90 separate side cylinders 16 each having a valve chest 17 and provide each cylinder and valve chest casting on one side thereof with suitable flanges 18 whereby said castings may be mounted upon the outer sides of the intermediate rectangular portion 6 of the respective side frames and rigidly fixed thereto by the bolts indicated as 19 or any other convenient fastening means which will permit of the easy and quick removal of the side 100 cylinders when necessary without disturbing the relative arrangement of the side frames 5 or the middle cylinder 7 and boiler saddle 10.

In a prior application for patent, Serial 105 No. 723,098, filed June 30, 1924, now Patent No. 1,630,901, dated May 31, 1927, I have described and claimed a locomotive frame structure wherein the side frames including the forward bumper extension and the rearwardly projecting parts to be bolted to the main frames together with the boiler cylin- 110

der saddle are cast in the form of a single integral structure. It will be seen that my present disclosure also includes as a part of this integral casting the central or middle cylinder of a three cylinder type engine together with its valve chest. It is to be observed that I preferably locate this middle or central cylinder between the side frames 5 in the same transverse line with the two side cylinders 16. The integral connecting wall between the central cylinder and the side frames, thus provides an ample reinforcement, securely strengthening and bracing the side frames at the point of connection of the two side cylinders 16 therewith so that the side frames are to a large extent, relieved of the severe mechanical strains or stresses which would otherwise be induced therein owing to the great weight of the side cylinder and valve chest castings. However, in this respect it will be understood that my present invention is not to be necessarily confined to the specific disclosure herein contained and that said central cylinder might be otherwise located between the side frames either forwardly or rearwardly of the two side cylinders. I have not herein shown the steam supply and exhaust connections for the several engine cylinders, since this is a matter of sound engineering judgment and constitutes no essential part of my present improvements.

It will be apparent to those who are familiar with modern locomotive design that by means of my present invention the ordinary two cylinder locomotive may be readily converted into one of the three cylinder type by merely substituting the front frame casting consisting of two side frames integrally connected by the central cylinder for the ordinary front frame and boiler cylinder saddle as heretofore provided.

It will be understood that the form of the two side frames and the side cylinder castings

as herein illustrated is merely suggestive, and that these parts may be produced in various forms, shapes and dimensions as may be deemed most desirable in accordance with the particular type of locomotive which is equipped with my present invention. It is therefore, to be understood that I reserve the privilege of resorting to all such legitimate changes in the form, construction and relative arrangement of the several parts as may be fairly embodied within the spirit and scope of the invention as claimed. 55

I claim:

1. In a locomotive engine of the three cylinder type, an integral structure comprising a middle cylinder, side frame members extending forwardly and rearwardly therefrom on opposite sides thereof, and a boiler seat saddle extending vertically above the middle cylinder; and side cylinders detachably secured upon the outer sides of said side frame members in transverse alignment with said middle cylinder. 60

2. In a locomotive engine, a one piece integral structure consisting of side frame members integrally connected intermediate of their ends by a transversely extending vertically positioned web and an engine cylinder and valve chest integrally formed with said web. 70

3. In a locomotive engine, a one piece integral structure consisting of side frame members integrally connected intermediate of their ends by a transversely extending vertically positioned web and an engine cylinder and valve chest integrally formed with said web, and a boiler seat saddle integrally formed with the upper end of said web above said cylinder. 75 80

In testimony that I claim the foregoing as my invention, I have signed my name hereto.

JOHN E. MUHLFELD.
